No. 660,148.

Patented Oct. 23, 1900.

C. W. DAVIS & H. M. HALL.

ADJUSTABLE BOOK REST.

(Application filed Feb. 8, 1900.)

(No Model.)

UNITED STATES PATENT OFFICE.

CHARLES W. DAVIS AND HUGH M. HALL, OF COLUMBIA, MISSOURI.

ADJUSTABLE BOOK-REST.

SPECIFICATION forming part of Letters Patent No. 660,148, dated October 23, 1900.

Application filed February 6, 1900. Serial No. 4,271. (No model.)

To all whom it may concern:

Be it known that we, CHARLES W. DAVIS and HUGH M. HALL, citizens of the United States, residing at Columbia, in the county of Boone and State of Missouri, have invented a new and useful Adjustable Book - Rest, of which the following is a specification.

This invention relates to book-rests, and more particularly to that class designed for supporting heavy volumes in position for writing, the object of the invention being to provide a structure in which the volume may be tilted to lie at various angles and in which it may be rotatably moved to facilitate inspection and also to provide means for holding the rest, with the book, at different points of its various adjustments.

In the drawings forming a portion of this specification, and in which similar numerals 20 of reference designate like and corresponding parts in the several views, Figure 1 is a side elevation showing the complete structure, with the book-receiving portion lying at an angle. Fig. 2 is a vertical central section of 25 the complete device, with the book-receiving portion lying horizontal. Fig. 3 is a detail perspective view showing the hinge connection between the spindle and the lug of the table.

Referring now to the drawings, the present invention comprises, preferably, a disk-shaped base 5, having supporting-casters 6 suitably attached to its under face and centrally of which disk is a hub 6^a, which extends above and below the disk-shaped base.

The hub 6^a is provided with a vertical bearing 7, extending entirely therethrough, and in this bearing is disposed the narrowed lower end 8 of a spindle 9, the upper end of which 40 is halved, as shown at 10, to receive a similarly-halved lug 11, disposed centrally of the under side of the book-supporting table 12. These halved portions are mutually connected through the medium of a screw 13, having a flange 14 to limit the movement of the screw 45 inwardly. The table 12 has a transverse groove 15 formed midway of its ends to receive the central portion of the back of a book, and at the rear edge of the table are 50 secured clips 16, each consisting of a U-shaped plate disposed to lie with the inner face of one of its sides against the under face of the

table and to lie with its opposite side above the upper face of the table, whereby the clips, which are of spring metal, may receive the 55 lower edges of the back of the book, so as to hold the back flat against the rest, so that the pages will lie flat to facilitate writing thereon.

The table 12 is adapted for rotatable adjustment, due to the pivotal bearing of the narrowed portion 8 of the spindle 9 in the bearing 7 of the hub 6^a, and in order to hold the table at different points of this rotatable adjustment a set-screw 17 is engaged with the hub 6^a below the disk 5 and is adapted to be 60 moved into and out of engagement with the narrowed portion 7 of the spindle. The table 12 is also adapted for adjustment upon the screw 13 to lie at various angles, and to hold the table at its different points of adjustment a slot 20 is formed transversely of the upper portion of the spindle 9, and in this slot is disposed an arc-shaped rack 21, one end of which is pivoted to a hanger 22, attached to the under side of the table, while 65 the opposite end of the rack has a cord 23 attached thereto at one end, the opposite end of the cord being attached to the screw 13, which is provided with an operating-handle 70 24. Normally the rack 21 lies in engagement with a knife-edge upon the plate 25, secured across the lower portion of the slot 20, and thus holds the table against pivotal movement. When it is desired to move the table, the screw 13 may be rotated slightly through 75 the medium of a handle 24, when the cord 23 will be wound upon the screw and the rack 21 will be moved from engagement with the plate 25. When the proper adjustment of the table has been secured, the rack may 80 be lowered into engagement with the plate.

In order to brace the laterally-extending portions of the table or rest 12, brace-plates 41 are provided, one end of each of which plates is serrated to form four arms 42, the 85 extremities of which arms are secured to the under side of the table at different points, while the body portion of the plate rests against the adjacent side of the spindle 9 slidably. This arrangement of the bracing- 90 plates permits the ready tilting of the table, but at the same time prevents the sides thereof from drooping. As illustrated in Fig. 2 of the drawings, the innermost arms of the 100

plates are attached to the table adjacent to the lug 11, while the outermost arms, which are longer, are attached to the table adjacent to its outer edges.

5 It will thus be seen that with the present device the book may be held at any desired angle and that the stand may be moved from place to place, as may be convenient, and that the table may be rotated to hold the 10 book in the proper position.

It will of course be understood that in practice the parts of the structure may be made of any suitable materials and that any proportions may be employed and also that modifications may be made without departing from the 15 spirit of the invention.

As illustrated in the drawings, the lower end of the lug 11 is rounded and is halved to engage the halved upper end of the spindle, 20 as shown at 10. The upper end of the spindle has a greater diameter than the lug and receives the lug in a recess in its face, this recess resulting in the formation of a stop which extends transversely of the lug to lie 25 in the path of movement thereof in one direction. This stop is so positioned that when the book-rest is brought to a horizontal position the lug will engage the stop, and if the ratchet then be engaged with the knife-edge 30 the rest will be held from movement in either direction.

What is claimed is—

1. A book-rest comprising a base, a spindle upon the base, a book-support pivoted to the

spindle, plates comprising arms attached to 35 the support at different points thereof and lying with their body portions in sliding contact with the spindle to brace the book-support at different points of its pivotal movement, and means for holding the book-support 40 at different points of its pivotal movement.

2. A book-rest comprising a base, a spindle journaled in the base, a book-support, a pivot-screw connecting the spindle and support and 45 adapted for rotation, a knife-edge carried by the spindle, a rack carried by the support and adapted for engagement with the knife-edge to hold the support at different points of its pivotal movement, and a cord connected with 50 the rack and with the pivot-screw for raising the rack from the knife-edge.

3. A book-rest comprising a base, a spindle upon the base, a book-support pivoted to the spindle, and plates comprising arms attached 55 to the support at different points thereof and lying with their body portions in slidable contact with the spindle to brace the book-support at different points of its pivotal adjustment.

In testimony that we claim the foregoing as our own we have hereto affixed our signatures in the presence of two witnesses.

CHARLES W. DAVIS.
HUGH M. HALL.
